[57] CLAIM

The ornamental design for a set of connectors for a computer, as shown and described.

DESCRIPTION

FIG. 1 is a front perspective view of a set of connectors for a computer showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The cord member has been shown in fragment in FIGS. 1 to 7 to indicate indeterminate length.
